UNITED STATES PATENT OFFICE.

CARLYLE W. THOMAS AND PHILIP W. SOMERS, OF BRIDGEPORT, CONNECTICUT,
ASSIGNORS TO THE SINGER MANUFACTURING COMPANY, OF ELIZABETH, NEW
JERSEY, A CORPORATION OF NEW JERSEY.

SEAM-MARGIN-OPENING DEVICE FOR SEWING MACHINES.

1,416,998.

Specification of Letters Patent. Patented May 23, 1922.

Application filed July 28, 1920. Serial No. 399,535.

To all whom it may concern:

Be it known that we, CARLYLE W. THOMAS and PHILIP W. SOMERS, citizens of the United States, residing at Bridgeport, in the county of Fairfield and State of Connecticut, have invented certain new and useful Improvements in Seam-Margin-Opening Devices for Sewing Machines, of which the following is a specification, reference being had therein to the accompanying drawings.

This invention relates to an improvement in the device disclosed in the United States patent of C. W. Thomas and F. E. Bradley, No. 1,365,747, dated January 18, 1921, and adapted to open the stitched margins of two superposed plies of material during the operation of uniting the same by a line or lines of stitching.

20 The present invention has for its primary object to completely fold back both of the margins of superposed plies of material rearward of the point of seam-formation during the operation of uniting the same by a line or lines of stitching, so that subsequent to the stitching operation and after opening the plies the united and folded margins present the appearance of having been ironed out.

30 Another object of this invention is to provide a presser-foot with a plurality of folding scrolls acting to complete the folding back of the margins of superposed plies of fabric rearward of the point of seam-formation.

35 The invention comprises stitch-forming and preferably trimming mechanism of well known construction, and in its preferred embodiment including a presser-foot having a material dividing tongue projecting forwardly from the heel portion of its tread-surface. The material-dividing tongue merges into an upper folding scroll, acting to fold back the margin of the upper ply of material and also into a lower folding scroll acting to fold back the margin of the lower ply of material. A throat-plate is employed having a portion thereof cut away to provide clearance for the lower folding scroll and to provide an aperture to permit a feeding element to operate upon the folded margins rearward of the folding scrolls to not only maintain the folded margins in proper position relatively to the fold-

ing scrolls, but also to crease the folded margins by its action against the tread surface of the presser-foot. Another feeding element is provided in advance of the folding scrolls in alignment with the latter and the feeding element previously referred to and serves to properly direct the material margins to the folding scrolls.

In the accompanying drawings Fig. 1 is an end elevation of a portion of a sewing machine embodying the present improvement. Fig. 2 is a view in elevation and partly in section of the mechanism illustrated in Fig. 1, but as viewed in the opposite direction. Fig. 3 is a perspective view of the throat-plate and feed-dogs of the sewing machine. Fig. 4 is a side elevation of the improved presser-foot. Fig. 5 is a bottom plan of the presser-foot. Fig. 6 is a rear end elevation of the presser-foot and throat-plate, illustrating in section the stitched, trimmed and folded material as it issues therefrom. Fig. 7 is a top plan view of the throat-plate, feed-dog and material dividing tongue in their relative operative positions and with the heel portion of the presser-foot shown detached from the latter. Fig. 8 is a sectional view of the product of the machine after the two plies of material are opened out, illustrating that the margins present the appearance of having been ironed down.

Referring to the drawings, the sewing machine is shown as constructed with a cloth-plate 1, into which is fitted the front slide-plate 2 and the throat-plate 3. The throat-plate is slotted for the passage of the feed-dog 4, carried by the feed-bar 5, which may be actuated in any suitable manner. The stitch-forming mechanism of the sewing machine is of well known construction, including a needle 6, carried by a needle-bar 7, and a loop-taker 8 cooperating with the needle, the construction details of the operating mechanism of which are unessential to an understanding of the present invention.

Opposed to the feed-dog 4 is a presser-foot 9, secured to the usual presser-bar 10. A portion of the tread surface of the presser-foot is partly cut away as at 11 to provide clearance for a resilient tongue 12, spaced slightly from said under-cut surface and formed at its forward end into a slightly upturned, transverse material-dividing plate

12'. The tongue 12 projects forwardly from a supplemental presser-plate 13, secured by means of screws, as 14, to the rear portion of the presser-foot so as to have its lower surface in alinement with the usual tread surface of the presser-foot.

The inner side of the tongue 12 merges into a curved surface or upper folding scroll 15 forming a side wall of a slot 16 cut into the plate 13. The lower surface of the tongue 12 merges into a downwardly and then inwardly curved surface or lower folding scroll 17 positioned below the scroll 15 and having its free edge spaced from the tread surface of the presser-foot. It will be observed that the scrolls 15 and 17 are effective to complete the folding of the margins of the material rearward of the point of seam formation, the needle aperture in the presser-foot being indicated at 18 and in the throat-plate at 19. It may be mentioned that the upper scroll 15 functions in a manner similar to the corresponding scroll disclosed in the prior patent hereinbefore referred to, the essential difference between the two constructions being the present provision of a lower folding scroll and cooperating devices to improve the product.

Cooperating with the lower scroll 17 to turn under the margin of the lower ply of material is an inclined edge 4' of an element of the feed-dog 4, which as particularly illustrated in Fig. 7 advances during the feeding movement of the feed-dog to a point immediately in advance of the free edge of the scroll 17, acting to crowd the margin of the material against said scroll to thereby assist in folding said margin. Further assistance toward this end is given by the element 4'' of the feed-dog 4, which acts on the folded margin rearward of the folding scrolls. This element 4'' of the feed-dog by its feeding action maintains the margins of the plies in proper position with respect to the folding scrolls so as to compel the latter to perform their function of folding said margins, i. e., it obviates any possible tendency of the margins to merely ride the curved surfaces of the scrolls without properly folding. The element 4'' of the feed-dog by its pressure, during feeding movement, against the tread surface of the presser-foot also serves to crease the folded margins so that they present the appearance of having been ironed. The space 20 provided intermediate the inclined edge 4' and the element 4'' of the feed-dog affords a clearance for the depending scroll 17 and it will be observed that the elements 4', 4'', 15 and 17 are substantially in alinement, this arrangement producing the more perfect work.

The trimming mechanism herein shown is of well known construction and comprises a stationary or ledger-blade 21 which may be formed integral with the throat-plate 3

or secured thereto as by means of a screw 22 and positioning pin 23. The ledger-blade is partly cut away at 24 to provide additional clearance for the lower scroll 17. A movable trimmer-blade 25 is adjustably secured by means of a screw 26 to the trimmer-blade carrier 27, mounted on a rock-shaft 28 supported in suitable bearings formed in the bracket 29 projecting upwardly from the cloth-plate of the machine. To the rock-shaft 28 is secured an arm 30 having a fork, embracing an eccentric 31 on an actuating shaft 32 and by means of which the trimmer is vibrated.

In operation, two superposed plies of material *m* and *m'* are passed underneath the presser-foot 9 to the stitch-forming mechanism and upon opposite sides of the resilient tongue 12, i. e., one above and one below said tongue. While being united by the stitches, the margins of the material are acted upon by the trimmer-blade 25 and severed closely adjacent to the outer edge of the tongue 12. As the trimmed margin of the stitched upper ply *m* is fed forward by the feed-dog, it abuts against the folding scroll 15, being turned upwardly and folded back upon itself. Likewise the margin of the lower ply *m'* abuts against the folding scroll 17, being turned downwardly and folded back upon itself so that when the plies of the finished product are opened out as shown in Fig. 8, the united margins are neatly folded back.

Having thus set forth the nature of the invention, what we claim herein is—

1. In a sewing machine, in combination, stitch-forming mechanism, feeding mechanism, and a plurality of folding scrolls concluding their folding action rearward of the point of seam formation to completely fold back a plurality of united margins of superposed plies of material in the operation of uniting the plies by stitches.

2. In a sewing machine, in combination, stitch-forming mechanism for uniting the margins of a plurality of superposed plies of material, feeding mechanism, and a presser-foot having a plurality of folding scrolls concluding their folding action in the rear of the point of seam formation to completely fold back a plurality of the margins of said plies.

3. In a sewing machine, in combination, stitch-forming mechanism for uniting the margins of a plurality of superposed plies of material, feeding mechanism, a plurality of folding scrolls in the rear of the point of seam formation, and a material dividing tongue merging into both of said scrolls.

4. In a sewing machine, in combination, stitch-forming mechanism, feeding mechanism, a presser-foot having a work-engaging tread surface, and an edge-turning scroll below the presser-foot tread surface rearward of the point of seam formation.

5. In a sewing machine, in combination, stitch-forming mechanism, a presser-foot having a work-engaging tread surface, an edge-turning scroll below the presser-foot 5 tread surface, and feeding mechanism including a feed-dog having an element terminating its feeding movement immediately in advance of said scroll.
6. In a sewing machine, in combination, 10 stitch-forming mechanism, a presser-foot, an edge-turning scroll rearward of the point of seam formation, and feeding mechanism including a feeding element having its entire feeding movement rearward of said 15 edge-turning scroll.
7. In a sewing machine, in combination, 20 stitch-forming mechanism, a presser-foot having a work-engaging tread surface, an edge-turning scroll below the presser-foot tread surface rearward of the point of seam
- formation, and feeding mechanism including a feeding element having feed movements rearward of said edge-turning scroll.
8. In a sewing machine, in combination, 25 stitch-forming mechanism, feeding mechanism including spaced and alined feeding elements, and an edge-turning scroll intermediate and alined with said spaced feeding elements.
9. In a sewing machine, in combination, 30 stitch-forming mechanism, feeding mechanism including spaced and alined feeding elements having feeding movements rearward of the point of seam formation, and edge-turning means intermediate said spaced 35 feeding elements.

In testimony whereof, we have signed our names to this specification.

CARLYLE W. THOMAS.

PHILIP W. SOMERS.
